United States Patent Office

Des. 212,257
Patented Sept. 17, 1968

212,257

SUCTION CLEANER

Harold W. Schaefer and Samuel E. Hohulin, Bloomington, Ill., assignors to National Union Electric Corporation, Stamford, Conn., a corporation of Delaware

Filed Nov. 13, 1967, Ser. No. 9,378

Term of patent 14 years

(Cl. D49—14)

Fig. 3.

Fig. 4.

Fig. 5.

FIG. 1 is a perspective view of a suction cleaner illustrating our new design;

FIG. 2 is a top plan view thereof;

FIG. 3 is a front elevational view thereof;

FIG. 4 is a side elevational view thereof; and

FIG. 5 is a rear elevational view thereof.

The dominant features of our design are shown in full lines.

We claim:

The ornamental design for a suction cleaner, substantially as shown and described.
